OBSTRUCTION WARNING LIGHT

Lester G. Scherer, Studio City, Calif.

Application March 12, 1956, Serial No. 40,570

Term of patent 14 years

(Cl. D72—1)

Fig. 1 is a top plan view of an obstruction warning light, showing my new design.

Fig. 2 is a front elevational view thereof.

Fig. 3 is a side elevation view.

The dominant features of the design are shown in full lines in the drawing.

I claim:

The ornamental design for an obstruction warning light, substantially as shown and described.
